UNITED STATES PATENT OFFICE.

CHARLES J. VAN DEPOELE, OF LYNN, MASSACHUSETTS.

ELECTRIC-RAILWAY MOTOR.

SPECIFICATION forming part of Letters Patent No. 424,911, dated April 1, 1890.

Application filed October 25, 1889. Serial No. 328,115. (No model.)

To all whom it may concern:

Be it known that I, CHARLES J. VAN DEPOELE, a citizen of the United States, residing at Lynn, in the county of Essex and State of Massachusetts, have invented certain new and useful Improvements in Electric-Railway Motors, of which the following is a description, reference being had to the accompanying drawings, and to the letters of reference 10 marked thereon.

My invention relates to electric motors of the class largely used for propelling electric-railway vehicles.

The general characteristics of the type of 15 motor to which my invention particularly relates comprise a self-contained machine, which is sleeved at its rear or yoke end upon the axle to be driven and flexibly supported at its front end, so as to have radial movement 20 with respect to its rear support. The armature-shaft is connected by gearing with the said axle to be driven, and is desirably geared down to such an extent that the employment of a counter-shaft and gearing becomes necessary. When the counter-shaft is omitted, 25 the matter is simplified and the rear end of the motor can be mounted directly upon the axle to be driven, said axle being provided with a gear-wheel large enough to extend into 30 engagement with a pinion upon the armature-shaft. Where, however, a counter-shaft is necessary, additional supports must be provided, and these have, up to the present time, as far as I am aware, always been 35 formed in side arms secured to the magnetic yoke of the machine. Necessarily a machine so constructed comprises a large number of parts and means for securing them together, each and all of which, aside from the expense 40 of manufacturing, are liable to become loose and inoperative in use. By my present improvement these objectionable features are entirely eliminated, which object is attained by forming the magnetic yoke, the side arms, 45 and the axle-bearings all in a single integral piece, which would almost without exception be formed by casting, although it might be otherwise produced, if desired. The motor-frame so constructed should be of soft iron, 50 and may be annealed, if desired, in order to avoid brittleness and liability to destruction.

The details of construction and arrange-

ment will be hereinafter set forth, and referred to in the appended claims.

In the drawings, Figure 1 is a plan view of 55 an electro-dynamic motor embodying my invention. Fig. 2 is a side elevation thereof, the gearing being indicated in dotted lines. Fig. 3 is an end view in which the field-magnet coils are shown in dotted lines. Figs. 4 60 and 5 are plan and end views, respectively, of my motor-frame without the field-magnet coils.

In said drawings, A represents the axle to be driven, usually provided at its extremities 65 with the carrying-wheels of a vehicle. B B' indicate bearings sleeved upon said axle, said bearings being integral with parts or arms b b' extending radially therefrom. The arms b b' sustain at or near their outer extremities 70 the ends of the shaft of the armature C, being provided for that purpose with suitable bearings C' C² properly secured therein. Intermediate between the armature-shaft bearings C' C² and the axle-bearings B B' are located 75 a second pair of bearings D D', within which is rotatably mounted a counter-shaft E. A driving-gear F is secured to the axle A, and said gear meshes with a pinion f upon the counter-shaft E. The counter-shaft carries, 80 also, a driving-gear G, which engages and is driven by a pinion g upon the armature-shaft. The motor-frame comprises the side arms b b', as stated, said arms being formed at their rear extremities into bearings resting upon the axle A. Said bearings are removable and engage only a part of said axle, substantially as indicated in Fig. 2, being secured in position by removable caps B² B³, which, together with the parts of the bearing 85 integral with the motor-frame, should be provided with suitable anti-friction lining. The side arms b b' are connected by a transverse rear portion or yoke H, with which they are integral.

The motor-frame is preferably composed of 90 soft cast-iron, and is specially designed to sustain the rear ends of the field-magnet cores and to form the magnetic yoke therefor.

I J indicate the field-magnet coils, through 100 which extend the iron cores, one of which i is seen in Fig. 1. The cores of the field-magnets I J are secured to and magnetically united by the yoke H. Obviously the said cores may be

connected to the yoke H in different positions, as endwise, as seen in Figs. 4 and 5; or they may be let into recesses formed therein, substantially as indicated in Figs. 1, 2, and 3. 5 When arranged as shown in said Figs. 1, 2, and 3, the rear ends of the field-magnet cores *i j* are let into oppositely-placed recesses in the yoke H and secured thereto by bolts *h*, which, for convenience of manufacture, may, 10 if desired, pass entirely through said cores and the intervening portion of the yoke. With this construction the motor-frame will possess great strength and rigidity, and, moreover, since both side arms are connected in permanent 15 relative positions a single set of boring-tools may be employed for positioning the bearings therein, thereby insuring greater exactness and permanency. If considered desirable, the yoke H may be re-enforced at the 20 part extending between the cores of the field-magnets, either to add structural strength where the same is recessed to receive the cores, as here shown, or to include still greater magnetic conductivity. 25 Various modifications of the structure herein shown may be made consistent with the foregoing description, which includes as its principal features the frame of a geared motor formed in one integral piece. Just how 30 the field-magnet cores are attached to that frame is of minor importance, as is also the character of the bearings employed for the different moving parts.

In Figs. 1, 2, and 3 the field-magnet cores 35 are seen as let into recesses in the yoke H. In Figs. 4 and 5 the yoke is not formed with recesses and the field-magnet cores are butt-ended thereto, being secured by screw-bolts O, which pass transversely through the yokes 40 H and enter the field-magnet cores longitudinally.

The field-magnet cores are seen in Figs. 4

and 5 without the magnetizing-coils indicated in the other figures.

Having described my invention, what I 45 claim, and desire to secure by Letters Patent, is—

1. A frame for an electric motor, comprising side arms and a magnetic yoke uniting the same, the arms and yoke being integral 50 with each other and formed of magnetic material, and field-magnet cores removably secured to and magnetically united by said yoke.

2. A motor-frame comprising side arms having bearings at one of their ends, whereby the 55 same are sleeved upon the axle to be driven, bearings at the opposite ends of the armature-shaft, a magnetic yoke connecting said arms and integral therewith, and field-magnet cores removably secured to and magnetically 60 united by said yoke.

3. A motor-frame comprising side arms having bearings at one of their ends, whereby the 65 same are sleeved upon the axle to be driven, bearings at the opposite ends of the armature-shaft, intermediate bearings for a counter-shaft, and a magnetic yoke connecting said arms and integral therewith, and field-magnet cores removably secured to and magnetically 70 united by said yoke.

4. A motor-frame comprising side arms having at their outer ends bearings for the armature-shaft, a magnetic yoke uniting their rear 75 ends and formed integral therewith, and downwardly-opening bearings at said rear ends for sustaining the motor-frame in a radially-movable position upon the axle to be driven.

In testimony whereof I hereto affix my signature in presence of two witnesses.

CHARLES J. VAN DEPOELE.

Witnesses:

J. WESLEY GIBBONEY,
FRANKLAND JANNUS.
